ABSTRACT: A thin, multisegment, incandescent lamp display which permits mounting of the device on the front surface of a control panel with no protrusions behind the front panel except wire or connecting terminations. Incandescent lamps with axially mounted filaments are directly viewed. The lamps are outside the apparatus on which the device is mounted and therefore do not contribute to internal heating.

ATTORNEY

THIN-LINE DIGICATOR DISPLAY

This invention relates to illuminated displays of the type wherein lamps are selectively energized to create a display.

BACKGROUND OF THE INVENTION

Seven-segment displays are commonly employed as readouts for a range of instruments such as digital voltmeters, computers, and the like. In order to obtain uniform lighting, it has been common practice to employ light guides for transmitting and fanning out the light from the tip of the conventionally tubular bulb-shaped incandescent lamp to the bar surface of the display segment. Such designs are shown, for example, in U.S. Pat. No. 3,252,158 and 3,261,013. The light output of this prior type of device was generally low and it was difficult to view in a well-lighted environment. Another of the problems faced by the user of such devices is that because of the light guide they generally extended for a great distance in the direction perpendicular to the plane of the display.

In the present design, axial filament-type lamps are employed for direct viewing and constitute the actual light bar segment. Thus the thickness of the display in a direction perpendicular to the plane of the display can be extremely small. For example, the overall dimension for a 1-inch character is but 0.265 inches thick by 1.43 inches high by 0.937 inches wide, when using light bars 0.075 inches wide. The display is legible at a distance of 50 feet in bright ambient daylight.

In addition, complete words may be printed on neutral or colored filters and may be used to indicate various functions, such as High Voltage On, Signal Received, a malfunction indication, Standby, Operate, etc., and may be placed in various arrangements in the housing.

Accordingly, it is a primary object of this invention to provide a segmented bar-type readout utilizing axial lamps for illumination.

It is another object of this invention to provide a multisegment display of thin dimension.

It is a further object of this invention to provide a multisegment display with increased light output for greater visibility.

Another object is to provide multiple readout displays where warnings of malfunctions or procedural functions may be displayed in color and combined with numerical displays.

A still further object of this invention is to provide a multisegment display with increased output and the capability of conveniently replacing individual lamps.

These and other objects, features and advantages of the invention will, in part, be pointed out with particularity and will, in part, become obvious from the following more detailed description of the invention, taken in conjunction with the accompanying drawing which forms an integral part thereof.

BRIEF DESCRIPTION OF THE DRAWING

In various FIGS. of the drawing, like reference characters designate like parts.

FIG. 1 is a front view of the display;

FIG. 2 is a top view of the display partially broken away along line 2-2, shown on a typical panel;

FIG. 3 is a cross-sectional view of the display taken along line 3-3;

FIG. 4 is a longitudinal, elevational view of an axial lamp;

FIG. 5 is a rear view of the main housing showing terminal means; and

FIG. 6 is an isometric view, partially broken away, of a printed circuit board with several lamps mounted thereon.

DESCRIPTION OF THE PREFERRED EMBODIMENT

Referring to the drawing, in FIG. 1 there is shown a typical thin-line display 10 comprising this invention, the display 10 providing a multisegment lighted numeric readout 12 and a plurality of functional readouts 14.

The display 10 is housed in a frame 16 that is comprised of longitudinal sections 18 and end sections 20. Sections of the frame 16 are provided with grooves 22 (FIG. 3) that are

dimensioned to accept a printed circuit assembly 24 (FIG. 6) which includes a conventional printed circuit board 26 having conducting pathways 28 on the rear surface thereof. The leads of a plurality of axial filament lamps 30 extend through the printed circuit board 26 and are electrically connected to selected ones of the conducting pathways 28. When selected ones of the lamps 30 are energized, a recognizable character is formed. One or more single-ended lamps 32 may also be mounted on the printed circuit board 26 so that when it is energized a decimal point is represented. Since the single-ended lamp 32 operates at a lower voltage than the axial filament lamps 30, a voltage-dropping resistor 34 is connected in series with the lamp 32 so that the display 10 operates from one potential. The foregoing describes the construction of the numeric readout 12. The functional readouts are provided by imprinting selected axial filament lamps 30 with suitable indicia as shown, for example, in FIG. 1.

A baffle member 36 is positioned over the printed circuit board 26 and is provided with a plurality of suitably sized and located apertures 38 which receive the axial filament lamps 30. The sides of the apertures 38 act to restrict the light emitted by the axial filament lamps 30 when they are energized. It is important to note that the filaments of lamps 30 are aligned in a common plane and, in combination with the sides of the apertures 38, provide for substantially improved readability of the display 10.

Mounting studs 40 are provided in the frame 16 and may be used for mounting the display 10 to a flat surface such as a panel P in cooperation with nuts 42. Mounting may be accomplished by drilling or punching simple panel openings and does not require carefully machined openings as for certain prior art devices.

The baffle member 36 described above is shown in the drawing as being plastic (nonconductive). When this construction is used only one insulator 44 is required between the rear surface of the printed circuit assembly 24 and the confronting surface of the panel P. The insulating material may be a sheet of mylar. However, the baffle member 36 may also be made of a suitable metal and in this instance, an insulator would be required between the rear surface of the baffle member 36 and the confronting surface of the printed circuit assembly.

A pair of terminal pins 46 are suitably secured to the printed circuit assembly 24 and extend rearwardly thereof through apertures 48 in the insulator 44. A conventional connector 50 is received in an opening 52 in the panel P and mates with the terminal pins 46. Another connector (not shown) is electrically connected to a suitable source of power and is adapted to mate with the connector 50. It should be understood that other terminal and connector formations may be used, including wiring directly to the terminal pins.

The resulting assembly is very compact and may be in the order of 0.3 inches thick by 1 1/4 inches high by 0.9 inches wide, with light bars or lamps which are only 0.09 inches wide. The display can be produced in character sizes of approximately one-fourth of an inch high to several inches high and character styles can be either alphanumeric or digital type.

A neutral or color filter 54 is provided over the face of the unit and serves to give a more uniform appearance to the light output as well as preventing dust or other foreign materials from entering. In addition, complete words or functions may be printed instead of one of the alphanumeric or digital displays.

As described heretofore, the display 10 may be formed of individual frame and baffle members. Alternatively, frame 16 and the baffle member 36 may be extruded in aluminum or may be molded of a synthetic resin such as polycarbonate, phenolic or other suitable resin. The display may be injection molded, die-cast or extruded in a strip into which may be stamped a multitude of openings of various configurations to receive the lamps. The printed circuit board may be a separate assembly or may be attached or deposited on the baffle member 36. Using current thick film techniques, the printed

circuit wiring and even the logic driving circuit may be deposited on the rear of the housing. The display may be cut into individual characters if desired, or, by placing several strips together, multicharacter displays or functions may be formed.

It is desirable to coat the inside of the apertures 38 with a reflective white paint to reflect the light. This results in a brighter, more uniform image.

If it is desired to "wire wrap" wires to connector pins 46, instead of using a connector, then a square pin 46 can be employed.

Accordingly, it will be appreciated that a flat, compact display is provided which can be mounted on the outside of the case for an electronic device. In this location the bulbs are outside the case and do not contribute to heating of components inside the case. Further, since the bulbs are on the outside they do not tend to overheat which would reduce their life.

While only the presently preferred embodiment of the invention has been illustrated, it is understood that alterations, changes and modifications may be made without departing from the true scope and spirit of the invention.

What I claim as new and desire to secure by Letters Patent is:

1. A thin, illuminable display adapted to be mounted on a panel, said display comprising;
  - a. a printed circuit board having first and second surfaces;
  - b. a plurality of lamps each having a tubular housing positioned coaxially about axially extending filaments that terminate in leads outside of said housing, said lamps being mounted on said first surface of said printed circuit board with the filaments of said lamps being aligned in a common plane, said leads of said lamps extending through said printed circuit board, selected ones of said lamps being adapted to be energized in response to a given set of input signals whereby said energized lamps form a recognizable character;
  - c. a plurality of conducting pathways formed on said second surface of said printed circuit board, selected portions of said pathways being electrically connected to said leads of said lamps; and

- d. baffle means positioned proximate said lamps for restricting the light emitted thereby through a said cylinder wall from being viewed from other than a specific segment of the recognizable character.
5. 2. The device in accordance with claim 1 wherein said baffle means is a nonconductive plate having apertures therein to receive said lamps, the sides of the apertures acting to restrict the light, said baffle means also having means integral therewith for mounting said device on the panel.
10. 3. The device in accordance with claim 1 wherein said baffle means is a conductive plate having apertures therein to receive said lamps, the side of the apertures acting to restrict the light, there being further included insulating means positioned between said baffle means and said first surface of said printed circuit board and between said second surface of said printed circuit board and the panel.
15. 4. The device in accordance with claim 3 further including frame means for supporting said baffle means and said printed circuit board, said frame means including means for mounting said device on the panel.
20. 5. The device in accordance with claim 1 further including filter means positioned over said lamps.
6. The device in accordance with claim 1 wherein at least one of said lamps includes indicia printed thereon.
25. 7. The device in accordance with claim 1 further including at least one single-ended lamp mounted on said printed circuit board, said single-ended lamp representing a decimal point when energized.
8. The device in accordance with claim 7 further including a voltage-dropping resistor connected in series with said single-ended lamp.
30. 9. The device in accordance with claim 1 wherein said printed circuit board includes terminal means adapted to be connected to an external source of electrical power.
35. 10. The device in accordance with claim 9 wherein said terminal means comprises a plurality of pins in electrical contact with selected portions of said conducting pathways and plug means adapted to mate with said pins, said plug means having portions to be connected to a suitable source of electrical power.
